NILS A. WAHLBERG, OF DERRY, PENNSYLVANIA, ASSIGNOR TO WESTINGHOUSE ELECTRIC & MANUFACTURING COMPANY, A CORPORATION OF PENNSYLVANIA

TRANSMISSION LINE DEVICE

Application filed February 4, 1929. Serial No. 337,249.

My invention relates to transmission-line devices and particularly to means for mounting field-control elements relative to high-voltage insulators.

- 5 One object of my invention is to provide a device of the above indicated character that shall be simple and durable in construction, economical to manufacture and effective in its operation.
- 10 Another object of my invention is to provide an insulator and a field-control element that may be readily mounted and dismounted relative to each other.

Another object of my invention is to prevent angular displacement between an insulator and a cooperating field control element therefor.

Another object of my invention is to provide an insulator that shall be adapted for 20 the selective reception of any of several field control elements of different character.

A further object of my invention is to provide an insulator and a field-control element that shall have a substantially plug and 25 socket connection between them.

The problem of attaching field-control elements, such as arcing horns, distributor rings and grading shields, to high-voltage transmission-line insulators, particularly of the 30 series-string suspension type, has been relatively difficult and expensive.

Various factors contribute to the difficulty of economically mounting the field-control elements, such as the relatively great lateral 35 extent of certain of the horns and rings, the small crowded space near the axis of the insulator where the elements are attached, the desirability of maintaining the elements in fixed position relative to the insulator, and 40 other considerations.

Further, where grading shields are placed between several of the units of a suspension insulator, considerations quite different from those in mounting horns and rings sometime 45 arise. A ring, unless divided, cannot be placed on or removed from a suspension insulator without detaching the insulator from its main support or from the conductor which it supports.

50 In general, there has been a wide diversity

between the means for attaching horns, rings, and shields and a change from one to another of these field-control elements has not been a simple or inexpensive matter.

It is my aim to overcome many of the objections heretofore arising in connection with controlling the fields of high-voltage suspension insulators. 55

Accordingly, in practicing my invention, I provide an insulator element and a joint or holding means that is so adapted for use in connection with either a horn, a ring or a shield as to render any one of these devices of itself more readily and economically adapted to the insulator and to render all of 60 them interchangeably so adapted. 65

Figure 1, of the accompanying drawings, is a top plan view of a device embodying my invention.

Fig. 2 is a side elevational view of the device shown in Fig. 1. 70

Fig. 3 is a view, similar to Fig. 2, of a modified form of my invention.

Fig. 4 is a view, in side elevation, of a series string of suspension insulator units, illustrating the invention as applied to voltage grading shields. 75

Fig. 5 is a view similar to Fig. 1 of a modified form of my invention, and

Figs. 6 and 7 are side views partially in elevation and partially in section of further modifications of my invention. 80

Referring to Figs. 1 and 2 the device here illustrated shows my invention as applied to the arcing horns.

The device comprises, in general, an insulator of a usual cap and pin type comprising a porcelain member 2 and a metal cap 3, and field control elements or arcing horns 4.

The cap 3 is provided with sockets or 90 grooves 6 of substantially dove-tail formation extending in the general direction of the longitudinal axis of the cap or of the insulator.

The arcing horns 4 are preferably constructed of strap metal having inner end portions 8 of substantially dove-tail formation for cooperation with the grooves 6 and outer end portions 9 for controlling the field or flash-over of the insulator. 95 100

While in Figs. 1 and 2, four of the grooves 6 are illustrated, any number of the horns 4, from one to four, may be employed therewith as desired, it being sometimes desirable to 5 confine flash-over to one local position along the insulator and sometimes to permit it at one or more other positions. There may further be a smaller or greater number of the grooves 6 or equivalent means for co-operation with one or a greater number of the horns 4, as above pointed out.

As shown, in Fig. 3, the insulator 2 and the cap 3 are similar to the insulator and cap in the previous figures, but, instead of the 15 horn or horns 4, a distributor ring 10 is provided.

The ring 10 comprises an annular or ring-like field-distributing portion 12 and radial supporting arms 14 therefore having inner 29 ends 8, similar to the ends 8 of the horns 4 in Figs. 1 and 2, for cooperation with the grooves 6.

In Fig. 4 a series of units, each comprising the insulator 2 and the cap 3 of the previous 25 figures, are illustrated, it being understood that the units of the other figures are for similar series-string suspension as illustrated in Fig. 4. However, in this form, instead of the arcing horns 4 or the rings 10, the caps 3 below the upper cap are provided with voltage-grading shields 16 of various sizes or surface areas in accordance with the voltage gradient desired.

In Fig. 4, the caps 3 are also similar to the 35 caps 3 in Figs. 1, 2 and 3, thus illustrating how the same caps are adapted for the selective reception of one of a variety of field controlling elements, which the horns 4, the ring 12 and the shields 16 constitute.

40 In the form of my invention shown in Fig. 5, the cap 3, instead of having longitudinally-extending dove-tail grooves or sockets 8, is provided with longitudinal dove-tail projections or flanges 18, and the arcing horn 4, or other field-control element is provided with a groove or grooves 19 for cooperation with one or a greater number of the projections 18.

50 In the form of my invention illustrated in Fig. 6, the grooves 6 and the projections 18 on the caps 3 of the previous figures are replaced by laterally projecting lugs 20 having longitudinal apertures 21 therein for the reception of inner end or ends 22 of an arcing horn or horns 23 or other of the elements 55 mentioned.

55 In each of the forms of my invention illustrated in Figs. 1 to 6, inclusive, the horns, rings and shields are placed in position by 60 simple downward thrust movements.

In the form of my invention shown in Fig. 7, the apertured lugs 20 of the structure shown in Fig. 6 are replaced by laterally and 65 upwardly projecting lugs 24 for the reception of an apertured downwardly and outwardly

projecting portion 25, representing an inner end of any of the elements 4, 10 or 16, which may be placed thereon by turning the horn portion through an angle of substantially 90°.

70 In any of the forms of the invention illustrated the field-control element may be permanently secured in position by merely peening over one of the adjacent ends of the field-control element or the holding means on the cap, or, where this peening operation is omitted, the field control elements may be readily removed and replaced by simple thrust movements.

75 By reason of the annular spaced relation of the holding means on the cap, such as the grooves 6, the projections 18 and the lugs 20 and 24, the field-control elements 4, 10 and 16 are held in fixed relation about the axis of the insulator.

80 The local positioning of the holding means on the cap may also be utilized for holding separable halves of the rings 10 and shields 16, in proper relative position, whereby these annular control elements may be readily removed and replaced, without disturbing the insulator connections.

85 By my invention, mounting and dismounting of the field-control elements are greatly facilitated, a selection of a variety of the elements is permitted for cooperation with the same holding means on the cap and other advantages are obtained which render the invention a distinct improvement in its field.

90 While I have shown and described particular forms of my invention, changes may be effected therein without departing from the spirit and scope thereof as set forth in the appended claims.

100 I claim as my invention:

1. A transmission-line device comprising an insulator of the cap-and-pin type and a field-control element, one of said cap and field-control elements having a substantially plug portion and the other a cooperating substantially socket portion for positioning the field element relative to the insulator.

110 2. A transmission-line device comprising an insulator of the cap-and-pin type and a field-control element, one of said cap and field-control elements having a substantially plug portion and the other a cooperating substantially socket portion for positioning the field element relative to the insulator, the axes of said portions being disposed aside, and extending longitudinally relative to the axis of the cap.

120 3. A transmission-line device comprising an insulator element and a field-control element one of which embodies a substantially plug portion and the other a cooperating substantially socket portion for fitting the elements together, the axes of said portions extending in the general direction of, and being 125

disposed aside, the longitudinal axis of the insulator.

4. A transmission-line device comprising an insulator of the cap-and-pin type, the cap having a plurality of holding portions, each constituting one element of a substantially plug-and-socket connector, spaced angularly thereabout, and field-control means held in position by said portions.

10 5. A transmission-line device comprising an insulator of the cap-and-pin type, the cap having a plurality of longitudinally-extending holding portions, each constituting one element of a substantially plug-and-socket 15 connector, spaced angularly thereabout, and field-control means held in position by said portions.

20 6. A transmission-line device comprising an insulator element and a field-control element one of which embodies a substantially dove-tail groove portion and the other a co-operating dove-tail portion for fitting the 25 elements together.

7. A transmission-line device comprising 30 an insulator element and a field-control element one of which embodies a substantially dove-tail groove portion and the other a co-operating dove-tail portion for fitting the elements together, said portions extending in the general direction of the longitudinal axis of the insulator.

8. A transmission-line device comprising 35 an insulator of the cap-and-pin type, a field-control element having a slip connection to the cap of said insulator and means for preventing displacement between the cap and the element.

9. A transmission-line device comprising 40 an insulator of the cap-and-pin type, a field-control element having a slip connection to the cap of said insulator in the general direction of the longitudinal axis of the insulator and means for preventing displacement of the element about said axis.

45 10. A transmission-line device comprising an insulator of the cap-and-pin type, the cap having a centrally-disposed mounting portion at its closed end and a portion constituting one element of a substantially plug-and-socket connector.

In testimony whereof, I have hereunto subscribed my name this 26 day of Jan. 1929.

NILS A. WAHLBERG.
